UNITED STATES PATENT OFFICE.

MATHEW HARDWIG, OF ST. JOSEPH, MINNESOTA.

AUTOMATIC-SEAL CHECK SAFETY-VALVE FOR RADIATORS.

1,204,979.

Specification of Letters Patent.

Patented Nov. 14, 1916.

Application filed March 31, 1916. Serial No. 88,022.

To all whom it may concern:

Be it known that I, MATHEW HARDWIG, a citizen of the United States, residing at St. Joseph, in the county of Stearns and 5 State of Minnesota, have invented certain new and useful Improvements in Automatic-Seal Check Safety-Valves for Radiators; and I do hereby declare the following to be a full, clear, and exact description of the 10 invention, such as will enable others skilled in the art to which it appertains to make and use the same.

The invention relates to an automatic seal check safety valve for radiators.

15 The object of the present invention is to improve the construction of that class of radiator valves which are interposed between the radiator and the return pipe and to provide a simple, practical and comparatively inexpensive automatic seal check safety valve adapted to permit the passage of air and water from a radiator and capable of confining the steam therein whereby the radiator is maintained at a high heating 25 efficiency.

A further object of the invention is to provide a safety valve of this character equipped with means for enabling it to be readily cleaned and the check valve renewed 30 without removing the body of the device from the radiator.

With these and other objects in view the invention consists in the construction and novel combination and arrangement of parts 35 hereinafter fully described, illustrated in the accompanying drawings and pointed out in the claims hereto appended, it being understood that various changes in the form, proportion and minor details of construction 40 may be resorted to without departing from the spirit or sacrificing any of the advantages of the invention.

In the drawings, Figure 1 is a longitudinal sectional view of an automatic seal 45 check safety valve constructed in accordance with this invention, Fig. 2 is a transverse sectional view on the line 2—2 of Fig. 1.

Like numerals of reference designate corresponding parts in the several figures of 50 the drawings.

In the accompanying drawing in which is 55 illustrated the preferred embodiment of the invention, the automatic seal check safety valve comprises in its construction a tubular body 1 comprising an inlet portion 2

and an outlet portion 3 and provided intermediate of its ends with a depending downwardly tapered tubular portion 4 forming a trap for the water of condensation to form 60 a water seal. The inlet end 2 which is designed to be connected with a radiator is inferiorly threaded at 5 and the outlet is exteriorly threaded at 6 to enable it to be connected by a union 7 with a return pipe 8 65 and an air pipe 9 but any other suitable means may be employed for connecting the valve with the radiator and the said pipe and while a union is shown it is not necessary to employ the same to facilitate the removal of the device as access to the interior 70 thereof may be readily had for cleaning the device or repairing the check valve as hereinafter fully explained. The body 1 is provided with a central depending transversely 75 disposed partition 10 preferably cored in casting to save metal and reduce the weight of the device and extending downwardly from the top of the body into the depending tubular portion 4 and terminating short of 80 the bottom thereof. The front and rear faces 11 and 12 of the transverse partition are preferably curved as shown and the enlarged top portion 13 of the partition is provided with oppositely inclined air passages 85 14 converging upwardly and terminating at a top opening 15. The body 1 is provided at the opening or socket 15 with an inferiorly threaded flange 16 receiving a screw plug 17 which is adapted to afford access to both of 90 the oppositely inclined air passages 14 for enabling the same to be readily cleaned. The lower depending portion 4 is also inferiorly threaded for the reception of a screw plug 18 which is adapted to be removed 95 for cleaning the bottom of the device should any sediment accumulate in the water seal portion.

The inlet portion 2 of the body 1 is equipped with an inclined check valve 19 100 hinged at the top at 20 and coacting with an inclined valve seat 21 and automatically closable against the same and adapted to be opened by water passing through the body from the radiator. The check valve 19 is 105 provided in its upper portion with a relatively small aperture 23 and it carries a flat valve 24 adapted to close under back pressure to enable the check valve to close entirely under such back pressure and prevent 110 air or water from returning to the radiator. The front portion of the body 1 is provided

at the top with an inclined tubular enlargement 25, arranged in alinement with the check valve 19 and having an interiorly threaded outer portion 26 for the reception 5 of a screw plug 27 adapted to be removed to afford access to the check valve and the supplemental valve 24 for closing the perforation 23. The body is also provided in rear of the transverse partition with a water 10 check 28 consisting of a valve hinged at the bottom at 29 and limited in its opening movement by a suitable shoulder 30. The bottom clean out plug 18 is adapted to afford access to the water check 28 which will 15 permit water to flow through the return pipe but prevent the return of the water thereby coacting with the main check valve 19.

What is claimed is:—

- 20 1. A device of the class described including a body having inlet and outlet portions and provided with an intermediate depending portion, said body being also provided at its intermediate portion with a transverse 25 partition extending downwardly into the depending portion and having an air passage through its upper portion, the said depending portion of the body being adapted to form a water seal and an automatically 30 closable check valve located in the inlet portion of the body and provided with an air passage.
2. A device of the class described including a body having inlet and outlet portions 35 and provided with an intermediate depending portion adapted to form a water seal, said body being provided at its intermediate portion with a transverse partition extending across the body and downwardly from 40 the top thereof into the depending portion, said partition being also provided in its upper portion with oppositely inclined air passages and having an opening communicating with the upper end thereof, remov-

able screw plugs for the said opening and 45 for the depending tubular portion and an automatically closable check valve arranged in the inlet portion.

3. A device of the class described including a body having inlet and outlet portions 50 and provided with an intermediate portion having a depending portion adapted to trap the water of condensation, said body being also provided at the intermediate portion with a transverse partition extending downwardly into the depending portion of the body, said body being provided at the inlet 55 portions with inclined valve seats and having an inclined tubular enlargement extending upwardly from the valve seats and provided with a removable closure and a hinged automatically closing check valve mounted within the inlet portion of the body and coacting with the said valve seats.

4. A device of the class described including a tubular body having horizontal inlet and outlet portions and provided with an intermediate depending tubular portion adapted to trap water of condensation, said body being also provided with a transverse 70 partition extending into the depending tubular portion and provided at the upper portion with an air passage, an automatically closable check valve located within the inlet portion of the body and provided with 75 an air passage, a valve carried by the check valve and adapted to close under back pressure and an automatically closable water check valve mounted in the depending portion of the tubular body and located in rear 80 of the transverse partition.

In testimony whereof I affix my signature in presence of two witnesses.

MATHEW HARDWIG.
